Primary Examiner — Philip S Hyder*Assistant Examiner* — Jerry Shiuan-Hua Hsu(74) *Attorney, Agent, or Firm* — Cambridge Technology Law LLC; Maura K. Moran**CLAIM**

The ornamental design for a glove with keyboard, as shown and described.

DESCRIPTION

FIG. 1 is a front perspective view of a glove with keyboard, showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a front elevational view thereof; and,

FIG. 7 is a rear elevational view thereof.

The dashed broken lines illustrate portions of the glove with keyboard that form no part of the claimed design. The dash dot broken lines depict a boundary line that forms no part of the claimed design.

1 Claim, 5 Drawing Sheets(56)
